CLAIM

The ornamental design for a sensual utensil set, as shown and described.

DESCRIPTION

FIG. 1 is a perspective view of the sensual utensil set, showing my new design;

FIG. 2 is a top plan view thereof;

FIG. 3 is a bottom plan of thereof;

FIG. 4 is a left side elevation view thereof;

FIG. 5 is a right side elevation view thereof;

FIG. 6 is a front elevation view thereof;

FIG. 7 is a back elevation view thereof;

FIG. 8 is a perspective view of the sensual utensil set, showing my new design;

FIG. 9 is a left side elevation view thereof;

FIG. 10 is a right side elevation view thereof;

FIG. 11 is a top plan view thereof;

FIG. 12 is a bottom plan view thereof;

FIG. 13 is a front elevation view thereof;

FIG. 14 is a back elevation view thereof;

FIG. 15 is a perspective view of the sensual utensil set, showing my new design;

FIG. 16 is a top plan view thereof;

FIG. 17 is a bottom plan view thereof;

FIG. 18 is a left side elevation view thereof;

FIG. 19 is a right side elevation view thereof;

FIG. 20 is a front elevation view thereof; and,

FIG. 21 is a back elevation view thereof.
